UNITED STATES PATENT OFFICE.

CHESTER M. DAVIS, OF BILOXI, MISSISSIPPI.

PACKING DEVICE.

Application filed November 20, 1925. Serial No. 70,360.

My invention relates to packing devices, and is employed in packing foods, such as shrimp or the like, also figs, pears, peaches and other fruits, in columns in glass tumblers or other receptacles.

The object of the invention is to provide a very simple, durable, and inexpensive device for quickly placing the articles one above the other in the glass or other receptacle so as to form the same into vertical columns, thereby giving the goods a fine appearance in the glass, showing their quality and size to the best advantage, and enabling the purchaser to quickly estimate the number of pieces in a glass.

Important features of the invention consist of a pin of any desired cross-sectional shape, adapted to be stood up in the middle of the glass to be packed, and, when desired, having a plurality of radiating wings extending outwardly an even distance from the pin.

The invention consists in certain novel features of construction and arrangements of parts relatively to each other and to the glass with which the device is to be used, as will be hereinafter described and claimed, reference being had to the accompanying drawings, in which;—Fig. 1 is a perspective view of the device removed from the glass or other receptacle with which it is to be used. Fig. 2 is a vertical section of a glass with the device standing in operative position therein. Fig. 3 is a top plan view of a glass with the device standing therein in operative position, and, Fig. 4 is a side elevation of a glass of shrimp that has been packed with the aid of my device.

The pin may be either provided with parallel sides, or it may be tapered from its upper end downwardly, being smallest at its lower end. The outer edges of the wings may also incline inwardly from top to bottom, to approximately correspond to the taper of the glass with which the device is intended to be used. And the parts of the device may be made of any desired material whatever.

Referring further to the drawings, the numeral 1 indicates the pin which may be of any desired cross-sectional shape, and may be either of even thickness, or may taper from top to bottom, as shown in the drawings. It is designed to extend above the top of the glass and has its upper por-

tion 2 formed into a handle portion, which is preferably round.

Extending outwardly from the sides of the pin 1 is a plurality of wings 3 removably secured in the pin, and inclining inwardly on their outer edges from top to bottom to correspond approximately to the taper of the glass with which the device is to be used, as is also the case with the pin illustrated in the drawings. It will be noted however that the taper of the wings is slightly greater than that of the glass, so that if the device should possibly come into positive engagement with the sides of the glass, such point of engagement will be preferably only at the upper end of the wings, and thereby the device will be prevented from any appreciable binding of the device in the glass.

The pin and wings may be made of any desired material suitable for the purpose of the device, and the pin is comparatively large relatively to the size of the glass, and has its upper portion 1^a projecting considerably above the top of the glass, so that the shoulders 4 will not interfere with the easy insertion of the shrimp or other goods into the glass at the sides of the pin.

In operation, the device is set in the glass to be filled, as shown in Figs. 2 and 3 of the drawings, and the shrimp or other products to be packed in the glass are dropped in at the sides of the pin between adjacent wings. It will be noticed that in the drawings a square pin is shown, and the wings are set diagonal to the sides of the pin, so that the pin presents flat faces between adjacent wings. As the glass is usually tapered, the smaller shrimp may be placed at the bottom of the spaces and the larger ones at the top. When the glass is filled the packing device is simply withdrawn. This leaves the shrimp all nicely arranged in columns in the glass.

Since the pin is comparatively large relatively to the size of the receptacle with which it is to be used, the pin can be used, even without the wings, to good advantage, as the sides of the pin form guides, as it were, for placing shrimp in the glasses. However, when the receptacle to be packed is large, the wings will be needed, and they may also be used to good advantage with the average-sized receptacle though as just stated very good packing may be effected

without the wings; but with unusually small receptacles, the pin by itself is all that is needed, and since the wings are detachably connected to the pin, a single one of the 5 devices is easily adapted for use with receptacles of different sizes.

Having now described my invention, it will be seen that I have provided a device of great simplicity and inexpensiveness, 10 which is nevertheless very effective in the performance of the functions required of it.

What I claim as new and desire to protect by Letters Patent is:—

1. A device of the character described, 15 comprising an elongated pin adapted to be used with a packing receptacle, said pin being of a comparatively large cross-sectional area relatively to the cross-sectional area of the packing receptacle with which it is to be used, and having a main body portion adapted to stand centrally in the receptacle 20 on the bottom thereof, and to project up a material distance above the top of the receptacle; and having a further upward extension at its upper end to form a handle portion.

2. A device of the character described, 30 comprising an elongated pin adapted to be used with a packing receptacle, said pin being of a comparatively large cross-sectional area relatively to the cross-sectional area of the packing receptacle with which it is to be used, and having a main body portion adapted to stand centrally in the receptacle 35 on the bottom thereof, and to project up a material distance above the top of the receptacle; and having a further upward extension at its upper end to form a handle portion; said pin having its main body portion exteriorly provided with a plurality of flat faces.

3. A device of the character described, 45 comprising an elongated pin adapted to be used with a packing receptacle, said pin being of a comparatively large cross-sectional area relatively to the cross-sectional area of the packing receptacle with which it is to be used, and having a main body portion adapted to stand centrally in the receptacle 50 on the bottom thereof, and to project up a material distance above the top of the receptacle; and having a further upward extension at its upper end to form a handle portion; said pin having its main body portion exteriorly provided with a plurality of converging flat faces corresponding in number to the number of columns to be packed in the receptacle, the lower end of the device being its smaller end.

60 4. A device of the character described, comprising an elongated pin adapted to be used with a packing receptacle, said pin being of a comparatively large cross-sectional area relatively to the cross-sectional area of the packing receptacle with which it is to be

used, and having a main body portion adapted to stand centrally in the receptacle on the bottom thereof, and to project up a material distance above the top of the receptacle; and having a further upward extension at its upper end to form a handle portion; said pin 70 having its main body portion tapered from its upper end toward its lower end, the lower end being the smaller end of the device.

5. A device of the character described, 75 comprising an elongated pin adapted to stand centrally in a packing receptacle, and provided with a plurality of radial wings extending outwardly a suitable distance for easy engagement with the interior walls of 80 the receptacle.

6. A device of the character described, comprising an elongated pin adapted to be used with a packing receptacle having its sides convergent from its top downwardly, 85 said pin being of a comparatively large cross-sectional area relatively to the cross-sectional area of the packing receptacle with which it is to be used, and adapted to stand centrally in the receptacle, the convergence 90 of the sides of the pin from its top toward its bottom corresponding approximately to the convergence of the sides of the receptacle.

7. A device of the character described, 95 comprising an elongated pin adapted to be used with a packing receptacle having its sides convergent from its top downwardly, said pin being of a comparatively large cross-sectional area relatively to the cross-sectional area of the packing receptacle with which it is to be used, and adapted to stand centrally in the receptacle, the convergence 100 of the sides of the pin from its top toward its bottom corresponding approximately to the convergence of the sides of the receptacle; and radial wings extending outwardly 105 from the sides of the device, said wings being also convergent to correspond approximately to the convergence of the receptacle.

8. A device of the character described, 110 comprising an elongated pin adapted to stand centrally in a packing receptacle, and provided exteriorly with a plurality of flat faces, and having as many radial wings as there are flat faces, the wings extending outwardly 115 from the corners formed by the meeting of adjacent faces.

9. A device of the character described, comprising an elongated pin adapted to stand centrally in a packing receptacle having its side walls convergent from top to bottom, said pin being exteriorly provided with a plurality of flat faces; and a plurality of radial wings equal in number to the number 120 of flat faces, the wings extending outwardly from the corners formed by the meeting of adjacent faces, both pin and wings being tapered from top to bottom to correspond approximately to the taper of the receptacle.

10. A packing device of the character de-

scribed, for use with receptacles of different sizes, comprising an elongated pin adapted to stand centrally in the packing receptacle, said pin being of a comparatively large cross-sectional area relatively to the cross-sectional area of the average-sized receptacle with which the device is to be used, and provided with a plurality of radial wings extending outwardly sufficiently to contact with the interior walls of the largest sized receptacle to be packed, said wings being removable to permit the pin alone, without the wings, to be used with small receptacles, and the pin and wings with the larger receptacles; whereby to adapt a single one of the devices for use with receptacles of different sizes. 15

In testimony whereof I affix my signature.

CHESTER M. DAVIS.
